FASTENER-APPLYING DEVICE

Charles B. Goodstein, Brooklyn, N. Y., assignor to
 Boston Wire Stitcher Company, Warwick,
 R. I., a corporation of Maine

Application August 16, 1938, Serial No. 225,122

14 Claims. (Cl. 1—3)

The present invention relates to improvements in fastener-applying devices for attaching papers and other sheets, securing tags and labels to articles of commerce and for use generally in fastening or stitching together various objects and articles.

One of the objects of the present invention is to provide a device of the type indicated having a coreless fastener-applying arm constituted as a magazine for holding a supply of U-shaped fasteners supported at the ends of their legs.

Another object of the invention is to provide a fastener-applying arm of the type indicated comprising parts which are relatively movable one with respect to the other to open the magazine in the arm to receive a supply of fasteners.

Another object of the invention is to provide a fastener-applying arm of the type indicated having one of its parts formed as a magazine for holding a supply of fasteners and a driver on the other relatively movable part for driving the fasteners from the magazine into the work.

Another object of the invention is to provide a fastener-applying arm of the type indicated having relatively movable parts pivotally mounted on a common axis adjacent one end and rockable one with respect to the other from an overlying nested relationship to an extended straight-line relationship to open the magazine.

Another object of the invention is to provide a device of the type indicated wherein a staple-pushers on one of the relatively movable parts of the fastener-applying arm is automatically retracted when the parts are moved relatively of each other to open the arm.

Still another object of the invention is to provide a device of the type indicated which is of extremely simple construction to adapt it for economical manufacture and assembly while being positive and efficient in operation to apply the fasteners to the work.

Further objects of the improvement are set forth in the following specification which describes a preferred form of construction of the device, by way of example, as illustrated by the accompanying drawings. In the drawings:

Fig. 1 is a side view of a fastener-applying implement incorporating the novel features of the present invention;

Fig. 2 is a longitudinal view of the implement, partly in section, showing the relationship of its parts at the completion of a fastener-applying operation;

Fig. 3 is a top plan view of the fastener-applying arm illustrated with the actuating lever or

cover removed to show the construction of the magazine for holding a supply of fasteners;

Fig. 4 is a perspective view of the implement illustrating the actuating lever or cover rocked on its pivot through an arc of 180° with respect to the magazine to retract the staple-pushers and open the arm to receive a supply of fasteners;

Fig. 5 is a transverse sectional view on line 5—5 of Fig. 2 showing the channel-shaped form 10 of the magazine and the U-shaped fasteners supported therein by the engagement of the ends of their legs with the bottom wall of the magazine;

Fig. 6 is a transverse sectional view on line 15 6—6 of Fig. 2 showing the depending flanges on the staple-pushers for retaining it in the magazine; and

Fig. 7 is a transverse sectional view on line 20 7—7 of Fig. 2 showing the common pivot for the magazine and lever of the fastener-applying arm and the springs for holding the arm raised with respect to the base and the lever raised with respect to the magazine.

In general, the present improved implement

25 comprises a base adapted to rest on a table, desk or other support and a fastener-applying arm hinged thereto. The fastener-applying arm comprises a channel-shaped magazine for holding a supply of U-shaped fasteners supported directly

30 on the bottom wall thereof, and an inverted channel-shaped lever serving as a cover for the magazine. The magazine is yieldingly held in raised position with respect to the base and the lever or cover is yieldingly held in raised position with respect to the magazine by a novel arrangement

35 of springs. The magazine and lever of the fastener-applying arm are mounted on a common pivot and the magazine is opened to receive a supply of fasteners by rocking the lever with respect to the magazine through an arc of 180° so that the staples may be inserted through the open top of the latter. During the relative movement of the lever and magazine a staple-pushers in the magazine is automatically retracted by

40 means of a flexible strap connecting the pusher with the lever. The fasteners are driven from the magazine by means of a staple-driver attached to the lever and reciprocable in a throat at the forward end of the magazine.

45 In the drawings the present invention is illustrated as applied to a device for driving and clinching U-shaped staples, but it is to be understood that the implement may be used to apply other forms of fasteners and the stapling arm 50 can be used independently of the base as a tacker

to drive staples or other fasteners without clinching their legs. As herein illustrated the implement comprises a rectangular base 2 having a raised boss 3 adjacent its forward end with clincher-grooves 4 formed therein and upwardly-projecting spaced ears or stanchions 5 adjacent its rearward end. Preferably, the base 2 is constructed in one piece blanked from sheet-metal stock with the boss 3 and clincher-grooves 4 stamped therein and the stanchions 5 folded upwardly at the sides thereof. The ears or stanchions 5 are drilled or otherwise pierced to provide alined holes 6 for mounting a pivot-pin 7.

The stapling arm 10 comprises a magazine portion 11 and a lever or cover 12 adapted to be nested one within the other. The magazine 11 and lever 12 constituting the arm 10 are both pivotally mounted on the laterally-projecting ends of the pivot-pin 7 for movement relatively of each other, or together as a unit. The magazine 11 is of channel-shape in cross-section, having a bottom wall 13 and upwardly-extending side walls 14 pierced with alined holes adjacent their rearward ends to receive the laterally-projecting ends of the pivot-pin 7. The bottom wall 13 of the magazine 11 has a central longitudinally-extending slot 15 terminating adjacent its opposite ends and providing opposite rails or tracks 16. Adjacent the rearward end of the bottom wall 13 the slot 15 is widened as shown in Fig. 3 to provide an opening 17 through which the ears 5 on the base 2 are adapted to project. A guide-plate 18 projects upwardly from the bottom wall 13 of the magazine at its forward end and flanges 19 project inwardly from the side walls 14 in spaced relation to the guide-plate to provide a throat 20 therebetween. Preferably, the bottom wall 13 is slotted rearwardly at its forward end adjacent the opposite side walls 14 and the portion between the slits is folded upwardly to form the guide-plate 18 and the projecting ends of the side walls are folded inwardly to form the flanges 19. Lugs 28 are also struck in from the opposite side walls 14 to provide rearward guiding means for the staple-driver and also means overlying the staples at the rear of the driver to prevent them from riding upwardly therewith.

The lever or cover 12 is of channel-shape in inverted relation with respect to the magazine 11 and has a top wall 21, depending side walls 22 and a front wall 23. The lever or cover 12 is slightly wider and longer than the magazine 11 so that its side walls 22 and its front wall 23 overlie the sides and front of the magazine. The side walls 22 are pierced adjacent their rearward ends to receive the laterally-projecting ends of the pivot-pin 7. Thus, the stapling arm 10 is comprised of two relatively movable parts adapted to be nested one within the other and pivotally mounted on the common pivot-pin 7. The rearward end of the lever 12 is open and the rearward edge of its top wall 21 is spaced a sufficient distance from the pivot-pin 7 to clear the rearward end of the magazine 11 and base 2 when the lever is rocked through an arc of 180° from the position illustrated in Fig. 1 to that illustrated in Fig. 4.

The arm 10 is normally sustained in raised position with respect to the base 2 by means of a leaf-spring 24 and the lever 12 is held in raised position with respect to the magazine 11 by means of a leaf-spring 25. The springs 24 and 25 are arranged with their ends overlying the bottom and top of the transverse web 26 at the 70

rear of the opening 17 in the bottom wall 13 of the magazine 11 and are both attached thereto by a pair of rivets 27. The spring 24 extends forwardly and downwardly to engage the base 2 at its free end; while the spring 25 is bent upwardly at an angle with its forward end engaging beneath the top wall 21 of the lever or cover 12. Preferably, the spring 24 is weaker than the spring 25 for a purpose as explained later.

10 In accordance with the present invention a supply of staples s may be inserted into the channel-shaped magazine 11 through its open top to be wholly supported therein by the ends of their legs resting on the bottom wall 13. The cross-bars of the staples s extend laterally across the interior of the magazine 11 which is so constructed that the opposite legs of the staples lie closely adjacent the inside faces of its spaced walls 14. Thus the magazine has no core, heretofore considered a necessary element, whereof to simplify the construction and reduce the number of parts.

15 The staples s are advanced in the magazine by a pusher 30 constructed in hollow form of folded sheet-metal. The pusher 30 is mounted on the magazine 11 at the rear of the staples s and has a top wall 31 and depending side walls 32 in alinement with the crossbars and depending legs of the staples. Folded inwardly from the bottom of the side walls 32 of the pusher 30 are flanges 33, see Fig. 6, which are adapted to slide on the tracks 16 at the opposite sides of the longitudinally-extending slot 15. The pusher 30 is retained in the magazine by means of depending runners 34 at its rearward end which project through the slot 15 and are folded outwardly to underlie the tracks 16. The pusher 30 is adapted to be advanced along the magazine 11 by means of a coil-spring 35. The spring 35 has one end attached to a lug 36 struck up from one of the flanges 33 of the pusher 30, thence it extends forwardly and is looped around a grooved stud 37 at the forward end of the magazine 11. From the stud 37 the spring 35 is stretched rearwardly and its opposite end anchored to a lug 38 bent inwardly from the side wall 14 of the magazine. As illustrated the central portion of the top wall 31 of the pusher 30 is formed with a forwardly projecting lip 43 adapted to overlie the crossbar of the rearmost staple, see Figs. 2 and 3, and a cam-face 39 extending upwardly and rearwardly from the forward edge of the lip and engageable by the driver when the last staple is in position to be driven or the supply of staples s is entirely exhausted. The pusher 30 is connected to the lever or cover 12 by means of a flexible strap 40 anchored to the rearward end of the top wall 31 of the pusher at 41 and to the top wall 21 of the lever at 42 by means of rivets or the like.

50 A staple-driver 45 is attached to the inside face of the front wall 23 of the lever 12 by means of a bolt 46, being held in spaced parallel relationship to the front wall by means of a spacer 47. The spacer 47 is of such dimensions as to align the staple-driver 45 with the throat 20 at the forward end of the magazine 11 to adapt it to reciprocate therein as the lever 12 is rocked downwardly with respect to the magazine. One preferred form of the invention having now been described in detail its mode of operation will be next explained.

55 To open the magazine 11 to adapt it to receive a supply of staples s the lever 12 is swung rearwardly on the pivot-pin 7 to the position illus-

trated in Fig. 4. During this rocking movement of the lever 12 to open the magazine 11 the point of attachment of the strap 40 on the lever is moved from one side to the other of the pivot-pin 7 to cause the staple-pusher 30 to be slid rearwardly in the magazine against the action of the spring 35. The implement, usually placed with its base 2 resting upon a desk or table, will then have the open top of the channel-shaped magazine 11 exposed. A supply of U-shaped staples s, preferably in the form of a self-contained stick such as illustrated and described in United States Letters Patent No. 1,792,235 issued to A. H. Maynard on February 10, 1931, is inserted in the magazine between its spaced side walls 14 with the ends of their legs resting upon the opposite longitudinal tracks 16. The staples s are thus wholly supported on the bottom wall 13 of the magazine 11 as the usual staple core or support has been eliminated. It will be noted that several of the staples of the stick at the rear of the driver 45 underlie the ends of the lugs 28 bent inwardly from the side walls 14 while the lip 43 at the forward edge of the pusher 30 overlies the rearmost staple of the stick. Thus the forward and rearward ends of the staple-stick are held from rising in the magazine 11 and the friction of adjacent staples pressed together by the spring 35 acting through the pusher 30 holds all of the staples in alinement. It has been found that the lugs 28 and lip 43 on the pusher 30 are sufficient to satisfactorily hold the staples from riding up in the magazine 11 during ordinary use of the implement. Thus all of the staples are held against the bottom wall 13 of the magazine 11 and advanced into the throat 20 beneath the driver 45.

With the magazine 11 loaded with staples as explained the lever 12 is rocked back to the position illustrated in Fig. 1 to cause it to overlie the sides of the magazine and close its open top. During the forward rocking movement of the lever 12 the strap 40 is slackened to release the staple-pusher 30 and the staple-driver 45 is entered into the throat 20. When released, the staple-pusher 30 is automatically slid forward by the spring 35 to advance the staples s in the magazine 11 and position the foremost staple in the throat 20. The implement is then ready for a staple-driving operation and the work w to be stapled is placed on the boss 3 at the forward end of the base 2.

The lever 12 is depressed and, due to the spring 24 being weaker than the spring 25, the arm 10 is rocked downwardly as a unit about the pivot-pin 7 until the forward end of the magazine 11 engages and clamps the work w against the boss 3 in the manner indicated in Fig. 2. Continued pressure on the lever 12 causes the spring 25 to yield and the driver 45 to descend through the throat 20. Thus, the foremost staple s is sheared from the remainder of the stick and driven through the throat 20 to cause its legs to penetrate the work and be clinched by the grooves 4 in the boss 3 on the base 2. During the driving of the foremost staple s the next adjacent staple straddles the guide-plate 18 and is supported thereon to provide a reaction to the shearing action of the driver 45 is severing the foremost staple. Upon release of the lever 12 the springs 24 and 25 act simultaneously to rock the arm 10 into elevated relationship with respect to the base 2 and to rock the lever 12 to raised relationship with respect to the magazine 11 as illus-

trated in Fig. 1. The driver 45 is thus withdrawn from the throat 20 and the staples s at the rear of the driver are held from upward movement therewith by their engagement with the ends of the lugs 28. It will also be observed that the forward edges of the lugs 28 provide rearward guides for the staple-driver 45. After the driver 45 has been withdrawn from the throat 20 the whole supply of staples s is advanced by the pusher 30 to position the next foremost staple in the throat 20. The device thus may be continuously operated by merely depressing the forward end of the lever 20 until the supply of staples s is exhausted. When the last staple of the stick is advanced into the throat 20 the lip 43 at the forward edge of the pusher 30 underlies the driver 45. During the descent of the driver 45 its bottom edge engages the cam-face 39 extending upwardly and rearwardly from the forward edge of the lip 43 of the pusher 30. The continual movement of the driver 45 as its edge rides on the inclined cam-face 39 on the pusher 30 acts to force the pusher rearwardly in the magazine 11 against the action of the spring 35.

It will be observed from the foregoing that the present invention provides an extremely simple and compact fastener-applying implement to adapt it for economical manufacture and assembly. It will be observed further that the stapling arm is of novel construction having a coreless magazine and an actuating lever which are relatively movable one with respect to the other to open the magazine to receive a supply of fasteners. It will be observed also that the present novel form of construction provides for automatically retracting the pusher during the relative movement of the relatively movable parts of the stapling arm so that the magazine may be loaded with facility.

While there is herein illustrated and described one preferred embodiment of the invention, it is to be understood that various modifications may be made in the structure and arrangement of the parts of the device without departing from the spirit or scope of the invention. Therefore, without limiting myself in this respect, I claim:

1. In a device of the type indicated, a channel-shaped magazine having an open side extending longitudinally thereof and parallel spaced-apart vertical flanges at one end forming a throat therebetween, said magazine being adapted to hold a supply of staples extending thereacross and supported therein by the engagement of the ends of their legs with the bottom wall thereof, a cover pivotally mounted on the magazine to overlie the open side of the latter, and staple-driving means carried by the cover and movable relatively of the magazine for driving the staples through the throat.
2. In a device of the type indicated, a magazine having a bottom wall with one end folded upwardly and side walls with their ends folded inwardly in spaced relation to the folded end of the bottom wall to form a throat therebetween, said magazine being adapted to hold a supply of staples extending across the magazine and supported therein by the engagement of the ends of their legs with the bottom wall thereof, and staple-driving means movable relatively of the magazine for driving the staples through the throat.
3. In a device of the type indicated, a channel-shaped magazine having a throat at one end through which the staples are driven and a lon-

itudinally-extending slot in its bottom wall, a pusher in the magazine for advancing the staples into the throat, said pusher having flanges extending through the slot in the bottom wall of the magazine and underlying said wall to retain it in the magazine, and staple-applying means movable relatively of the magazine for driving the staples through the throat.

4. In a device of the type indicated, a one-piece channel-shaped magazine of a width to adapt it to hold a supply of staples extending thereacross with their legs engaging its opposite sides, said staples being supported in the magazine by the direct engagement of the ends of their legs with the bottom wall thereof, a pusher in the magazine, means for sliding the pusher along the magazine, staple-driving means movable relatively of the magazine for driving the staples as they are advanced by the pusher, and means on the sides of the magazine at the rear of the staple-driving means and on the forward edge of the pusher for overlying the forward and rearward staples in the magazines respectively.

5. In a device of the type indicated, a base, a stapling arm comprising a one-piece channel-shaped magazine pivotally mounted on the base for movement toward and away from the latter, said magazine having an open side extending longitudinally thereof throughout a substantial portion of its length, and a pivoted cover closing the open side of the magazine and rockable on its pivot to open the magazine to adapt staples to be supplied through its open side, said staples being supported in the magazine by the direct engagement of the ends of their legs with the bottom wall of the magazine.

6. In a device of the type indicated, a base having clincher-grooves at one end and a pivot at its opposite end, a channel-shaped magazine rockably mounted on the pivot on the base, the bottom wall of said magazine having a central slot providing opposite tracks for supporting a supply of staples, a pusher slideable on the magazine and having retaining flanges extending through the slot in the bottom wall and engaging the under side of the staple-tracks, a channel-shaped cover rockably mounted on the pivot on the base at one end and having a driver at its opposite end for driving staples from the magazine into engagement with the clincher-grooves on the base, said cover being rockable away from the magazine to open the latter to receive a supply of staples, and a flexible strap connecting the cover and pusher for retracting the latter when the cover is moved with respect to the magazine to open the latter.

7. In a device of the type indicated, a base, a magazine pivotally mounted on the base for movement toward and away from the latter and having a bottom wall, a pivotally mounted cover overlying the magazine, and a pair of springs having one of their ends connected to the bottom wall of the magazine and their free ends engageable with the base and the cover respectively to hold the magazine raised with respect to the base and the cover raised with respect to the magazine.

8. In a device of the type indicated, a base having clinching means adjacent one end and upstanding ears adjacent its opposite end, a magazine having a bottom wall with an opening therein through which the ears on the base project and providing a transverse web at the rear of the opening, a cover overlying the magazine,

5 a pivot-pin extending transversely through the cover, magazine and ears on the base, and a pair of springs having one of their ends fastened to the transverse web on the magazine, the free ends of the springs being engageable with the base and cover respectively to hold the magazine raised with respect to the base and the cover raised with respect to the magazine.

9. In a device of the type indicated, a magazine-arm for holding a supply of staples, said magazine-arm having a bottom wall with one end folded upwardly and side walls with their ends folded inwardly in parallel spaced relation to the folded end of the bottom wall to form a throat therebetween, and staple-driving means movable relatively of the magazine for driving the staples through the throat.

10. In a device of the type indicated, a magazine having an opening in its side extending longitudinally thereof through which staples may be supplied thereto, a lever movable relatively of the magazine for closing the opening therein, and a driver operated by the lever, said lever being movable toward the magazine to drive staples therefrom and away from the magazine to open the latter to receive a supply of staples through the opening in its side.

11. In a device of the type indicated, a base, a magazine having an opening in its top extending longitudinally thereof through which staples may be supplied thereto, a lever for closing the opening in the top of the magazine, a driver operated by the lever, and a pivot-pin extending through the base, magazine and lever to connect them for relative movement, said magazine being rockable on the pivot-pin with respect to the base and said lever being rockable on the pivot-pin toward the magazine to drive the staples and away from the magazine to open the latter to receive a supply of staples through the opening in its top.

12. In a device of the type indicated, a magazine for staples having an opening in its top extending longitudinally thereof through which staples may be supplied thereto and a throat through which the fasteners are driven therefrom, a pusher in the magazine for advancing the staples to the throat, a lever movable relatively to the magazine for closing the opening therein, and a driver mounted on the lever and adapted to reciprocate in the throat of the magazine to drive staples therefrom upon relative movement of the lever toward the magazine, said lever being movable away from the magazine to open the latter to receive a supply of staples through the opening in its top.

13. In a device of the type indicated, a base having clinching means thereon, a magazine for staples having an opening in its top extending longitudinally thereof and a throat through which the staples are driven, a pusher in the magazine for advancing the staples to the throat, a lever overlying the opening in the top of the magazine, a driver mounted on the lever and adapted to reciprocate in the throat in the magazine, and a pivot-pin extending through the base, magazine and lever to pivotally connect them for relative movement, said magazine being rockable on the pivot-pin with respect to the base and said lever being rockable on the pivot-pin toward the magazine to drive staples through the throat and rockable away from the magazine to open the latter to receive a supply of staples through the opening in its top.

14. In a device of the type indicated, a magazine having a chamber for holding a supply of staples, said magazine having a throat at one end through which the staples are driven and a longitudinally-extending slot at the bottom of the chamber, a pusher in the magazine for advancing the staples to the throat, said pusher

5 having flanges extending through the slot in the magazine and underlying the latter to retain it therein, and staple-applying means movable relatively of the magazine for driving the staples through the throat.

CHARLES B. GOODSTEIN.
